(57) **CLAIM**

The ornamental design for a shingle, as shown and described.

DESCRIPTION

FIG. 1 is a top plan view of the shingle of our design.

FIG. 2 is a right side edge view of the shingle of FIG. 1. The left side edge view of the shingle of FIG. 1 is a mirror image of FIG. 2.

FIG. 3 is a bottom edge view of the shingle of FIG. 1. The top edge view of the shingle of FIG. 1 is a mirror image of FIG. 3.

FIG. 4 is a rear view of the shingle of FIG. 1; and,

FIG. 5 is a top, right edge and bottom edge perspective view of the shingle of FIG. 1.

The broken lines are for illustrative purposes only and form no part of the claimed design.
